UNITED STATES PATENT OFFICE.

JAMES F. ROWLEY, OF CHICAGO, ILLINOIS.

COAPTATING-PAD.

1,099,938.

Specification of Letters Patent. Patented June 16, 1914.

Application filed June 19, 1912. Serial No. 704,583.

To all whom it may concern:

Be it known that I, JAMES F. ROWLEY, a citizen of the United States of America, and a resident of Chicago, county of Cook, 5 State of Illinois, have invented certain new and useful Improvements in Coaptating-Pads, of which the following is a specification.

The object of this invention is to provide 10 an improved coaptating pad for artificial limb sockets which is substantially free from parts or materials causing friction on the stump of the wearer, and which will at the same time provide means for properly holding in place a plastic material which controls the shape of the pad.

An illustrative embodiment of this invention is shown in the accompanying drawings, in which—

20 Figure 1 is a vertical section of an artificial leg socket with a coaptating pad made in accordance with this invention, and showing the stump of the wearer in place therein. Fig. 2 is an enlarged section taken on the 25 line A—A of Fig. 1.

The coaptating pad or socket member is formed of a flexible lining 10 and a soft plastic base or filling 11 which is secured to the inner face of the body 12 or main part 30 of the artificial leg.

Before the present invention, artificial limb sockets and coaptating pads which were made according to my Patent No. 526,057, of September 18th, 1894, to a great 35 extent avoided previous objections to other artificial limb sockets. Some of these objections were that ordinary pads were rigid and caused local pressure and inflammation, and that elastic pads while coaptating caused 40 undue friction and pressure on the tender stump of the wearer. Moreover the pads commonly used were not entirely free from materials which chafed the wearer's stump leg. Some of these made under my 1894 45 patent had the inner lining made of canvas which came in contact with the stump leg of the wearer, as described in my said patent, and others had said inner lining made of leather. In the latter it was found neces-

50 sary, in order to prevent relative shifting of the lining and main part or plastic part, to provide an annular seam or stitches sewed at other parts of the interior of the socket. All of said seams or stitches caused a chafing 55 on the skin of the wearer, due either to the stitches themselves or to a depression or val-

ley at the stitch line. When canvas was used, as in my said patent of September 18th, 1894, the meshes of the canvas frequently formed a surface which chafed the 60 skin of the wearer. The present invention overcomes these objections by eliminating both the canvas and the stitches. This may be done by using a soft pad at 11 which has one face at 13 made preferably of soft meshed 65 fabric, and has the main thickness or body thereof made of a soft woolly, absorbent material suitable for becoming saturated with paraffin wax or other plastic material which serves to retain the pad in proper 70 shape to fit the stump of the wearer.

The face 13 should be suitable to be cemented to the inner lining, which is preferably made of leather, and is also preferably saturated with the plastic material. This 75 pad may be made of eiderdown cloth, canton flannel, or a thick cotton flannel or the like, in which the main part or body part is saturated with paraffin wax or other waxy or like plastic material. The meshed fabric 80 part or that face which is of greater tensile strength than the body of the material, being less absorbent, takes up less of the waxy or plastic material, and therefore provides a surface which can be cemented to the inner leather lining 10, which is also impregnated with some of the plastic material, but not sufficient to interfere with the action of the cement.

It is not necessary that the lining 10 and 90 fabric face of the pad 11 be so securely cemented as to prevent them from being peeled apart when the pad is not in position in the leg, but the cement should hold sufficiently 95 to prevent a relative slipping of the leather lining 10 and the pad 11. The pad and lining may be cemented together before impregnation with the plastic material. Care must be taken that the quantity of cement used in any case is not sufficient to interfere 100 with the plastic or coaptating quality of the pad.

The pad 11 and its lining 10 are secured to the body 12 of the artificial leg by any suitable means which holds the pad and body 12 105 against relative longitudinal or vertical shifting. This may be accomplished by flaring out the upper part of the lining at 14 and having the lower part of the pad rest upon the shoulder 15 formed in the part 12 110 of the artificial leg.

To fit the pad or socket to an artificial

leg, the socket is first warmed sufficiently to soften the plastic material. When the stump of the wearer is then inserted in proper position, the pad readily conforms to the shape of the stump, and retains warmth shape upon cooling. The natural warmth of the stump retains the plastic material in a softened state while on the stump, thus forming a continuously and constantly coaptating pad in which the parts are retained in proper relative position, and which may be made entirely free from any chafing seams or stitches.

Although but one specific embodiment of this invention is herein shown and described, it will be understood that numerous details of the construction shown may be altered or omitted without departing from the spirit of this invention, as defined by the following claims.

I claim:—

1. A coaptating pad for artificial limbs, comprising a woolly base and a suitable

leather lining cemented thereto, said base and lining being permeated with a melted substance adapted to remain plastic at a temperature bearable by the human body.

2. A coaptating pad for artificial limbs, comprising a base of pliable material permeated with a waxy substance adapted to remain plastic at a temperature bearable by the human body, and a lining cemented to one face of said base.

3. A coaptating pad for artificial limbs, comprising a base of pliable material permeated with a waxy substance adapted to remain plastic at a temperature bearable by the human body, said base being faced with a fabric and a lining cemented to said fabric.

Signed at Chicago this 14th day of June 1914.

JAMES F. ROWLEY.

Correction in Letters Patent No. 1,099,938.

It is hereby certified that in Letters Patent No. 1,099,938, granted June 16, 1914, upon the application of James F. Rowley, of Chicago, Illinois, for an improvement in "Coaptating-Pads," an error appears in the printed specification requiring correction as follows: Page 2, line 5, for the word "warmth" read *such*; and that the said Letters Patent should be read with this correction therein that the same may conform to the record of the case in the Patent Office.

Signed and sealed this 7th day of July, A. D., 1914.

[SEAL.]

R. F. WHITEHEAD,

Acting Commissioner of Patents.
